KERF-CUTTING MACHINE

Thomas E. Pray, Chicago, Ill., assignor to Goodman Manufacturing Company, Chicago, Ill., a corporation of Illinois

Application October 14, 1940, Serial No. 361,030

2 Claims. (Cl. 262—30)

This invention relates to improvements in kerf-cutting machines adapted to cut a horizontal kerf in the mine wall along the roof or at various intermediate positions between the roof and floor.

One of the principal objects of the invention is to combine the relatively high cutting capacity of heavy-duty kerf-cutting machines of the type heretofore mounted on wheeled trucks and operated on the mine track, with the decreased height and greater flexibility of movement attained by room and pillar and longwall machines, which are slideable along the mine floor by means of cables. Other objects of the invention will appear from the following description.

The invention may best be understood by reference to the accompanying drawings wherein:

Figure 1 is a fragmentary plan view of a mining machine constructed in accordance with my invention, and with parts broken away to show certain gearing details;

Figure 2 is a side view of the machine shown in Figure 1, with parts broken away to show certain gearing details;

Figure 3 is a detail section taken on line 3—3 of Figure 1;

Figure 4 is a detail section taken on line 4—4 of Figure 1;

Figures 5 and 6 are enlarged detail sections taken on lines 5—5 and 6—6, respectively, of Figure 1.

Referring now to details of the embodiment of my invention illustrated in the drawings, 10 indicates generally a skid adapted to slide universally over the mine floor, and forming the base frame and main support for the machine. Said skid is in the form of a flat plate 11 having marginal side flanges 12, 12, rear flange 13, and front flange 14.

A relatively wide turntable 15 is rotatably mounted close to the top of the skid plate 11, the adjacent portions of the side and front marginal flanges of the latter being cut away to accommodate the projecting edges of said turntable. In the form shown herein, the rotatable mounting for the turntable comprises a flat annular bearing 17 fixed to the bottom plate 11, supporting an annular bearing ring 18 formed on the bottom of the turntable 15 and secured to the latter by a detachable outer ring 19, as shown in Figure 3.

Mounted on the turntable is a cutting mechanism supporting means indicated generally at 20, affording vertical adjustment and transverse tilting for a cutter bar 25. The supporting means

shown herein is in the main similar to that shown in my U. S. Patent No. 2,102,743, issued on Dec. 21, 1937, and includes as its principal elements a pair of vertically extending guide frame members 22, 22, between which is mounted a vertically adjustable cradle 23 having a frame 24 trunnioned therein for tilting on a transverse axis. The frame 24 forms a support for the rear end of the cutter bar 25, and carries a motor 26 operatively connected with a cutter chain 27 of said cutter bar, and also having gearing driven thereby for adjusting the cradle 23 vertically relative to said guide frame members.

The frame 24 is provided with a pair of oppositely disposed bored bosses 28 extending laterally therefrom intermediate the ends of said frame. Each of said bosses has a bored trunnion support member 29 mounted therein and extending laterally therefrom. Each of said trunnion support members is journaled in a side frame member 30 of the cradle 23 in such a manner that the entire frame 24 with its cutter bar may be tilted about the transverse axis defined by said trunnion supports.

The side frames 30 of the cradle 23 extend along the frame 24 and are guided for vertical movement between the vertical guide frame members 22. Each of said guide frame members has a pair of vertically disposed racks 32 at opposite ends thereof, said racks being meshed with pinions 33, 33 on the opposite ends of longitudinally extending shafts 34, 34 rotatably supported at opposite ends of said side frames 30. Each shaft has a worm gear 35 keyed thereto and disposed in a housing 36 formed integral with its respective side frame, the upper portion of which housing also forms the bearing support for the adjacent trunnion support member 29. Said worm gears are meshed with worms 37, 37 on the opposite ends of a transversely extending shaft 39, which extends coaxially through the trunnion support members 29, 29.

The transverse shaft 39 has a helical gear 40 thereon, driven by a helical pinion 41 on a stub shaft 42 disposed longitudinally of the frame 24 adjacent the central portion thereof, as shown in Figures 1 and 3. A main shaft 45 extends longitudinally forward from the motor 26 and is connected thereto by a gear 46 meshing with a motor pinion 47. The helical pinion 41 and shaft 42 are selectively driven by said main shaft in reverse directions through a reversing gear mechanism of any well known form, such as that disclosed in my Patent No. 2,102,743, and including opposed sliding clutch members 48 and 49 on

the main shaft 45 adapted to drive the sleeve 42 either through gears 50 and 51 or gears 52, 53 and 54.

The cradle 23 and frame 24 may be adjusted vertically relative to the guide frame members 22, 22, and will be held in fixed relation with respect thereto by means of the worms and worm gears, 37 and 35, which are of the usual self-locking type.

The main shaft 45 also drives the cutter chain 27 about the cutter bar 25 through a suitable gear train, herein including a bevel pinion 55, bevel gear 56, sprocket shaft 57 and sprocket 58, all carried at the forward end of the frame 24.

Means are provided for tilting the frame 24 and the cutter bar about the trunnion supports, as herein shown such means including an outboard support 60 including arms 61, 61 extending forwardly from the side frame members 30 of cradle 23 and having a gear housing 62 trunnioned in the forward end thereof at 63, 63. A worm gear 64 is mounted in the housing 62 on a vertical axis, and is driven by a worm 66 on transverse shaft 67, journaled in said housing. An upright screw shaft 68 is threaded in the worm gear 64 and extends upwardly into pivotal connection at 65 with the forward end of the tilting frame 24 beneath cutter bar 25, as is clearly shown in Figures 2 and 3. The opposite ends of shaft 67 extend freely through the arms 61, 61 of the outboard support 60, and have hand wheels 69, 69 thereon, to permit tilting adjustment of the frame 24 and cutter bar 25 relative to the cradle 23, from either side of the machine.

Referring now to the mechanism for transporting the machine about the mine and for moving it into cutting position, a pair of cable drums 70, 70 are mounted at opposite sides of the base frame or skid 10, as herein shown said drums being rotatably mounted on a transverse shaft 71 extending from one side of the machine to the other, and journaled in the upright side flanges 12, 12 of the base frame. Said drums are of similar form and arrangement to those heretofore used in shortwall mining machines, being provided with cables 72, 72 which may be selectively trained about sheaves 73, 73, supported by projecting brackets 73a, 73a at the front corners, and by sheaves 74, 74 supported by projecting brackets 74a, 74a at the rear corners of the main frame 10. The cables 72, 72 can be trained over said sheaves so as to maneuver the machine as a whole universally over the mine floor, in the usual manner, by anchoring the ends of said cables in any desired direction and drawing in said cables by power or paying them out under frictionally controlled resistance. In the form shown herein, the drums 70 are each arranged to be connected for rotation from the cross-shaft 71 by an ordinary pin clutch 75 carried by web 76 of the drum, and adapted to be detachably engaged with a hub member 77 keyed to the shaft 71. Each drum also has a friction band 78 associated therewith, arranged to retard rotation thereof in the usual manner when its respective cable is to be payed out under frictional resistance.

The drums 70 are driven from a motor 60 mounted adjacent the rear of bed plate 11, and connected to the cross shaft 71 through a planetary gear reduction device indicated generally at 81 and a reversing clutch mechanism indicated generally at 82.

The planetary gear reduction device 81 is of a familiar type for providing two driving speeds under frictional control of friction bands 63 and 75

84, as heretofore employed in flexible feed drives for mining machines, so details of such planetary device need not be described herein. A driven shaft 85 of said planetary has a bevel pinion 86 of the reversing mechanism 82 which is also of a well known form, including bevel gears 87, 88 loosely mounted on shaft 71 and selectively connected thereto by a sliding clutch member 89 feathered on said shaft between said bevel gears. 10 By the gearing arrangement just described, the cross shaft 71 can be driven in reverse directions at a plurality of frictionally controlled speeds.

The turntable 15 is also swung by power of the motor 80 for feeding the cutter bar arcuately 15 across the front of the machine. For this purpose, a worm 90 is loosely mounted on the cross shaft 71, and is selectively connected thereto by sliding clutch member 91. A worm gear 92 is rotatably mounted on a vertical shaft 93 in housing 94. A chain sprocket 95 is mounted on the lower end of shaft 93 and has a chain 96 trained thereabout which extends around the turntable 15. Since the cross shaft 71 can be reversely driven at a plurality of speeds, as previously described, the turntable can be swung in either direction by proper manipulation of clutch 91, reversing mechanism 82, and planetary 81. This chain drive for the turntable provides not only a simple and effective swinging mechanism, but assists in keeping the height of the machine to a minimum.

A plurality of screw jack members 97, 98 and 99 are carried by the base frame 10 for tilting the machine bodily relative to the mine floor, and 35 for anchoring the base frame relative to the mine floor during cutting. In the form shown herein, screw jacks 97 and 98 are mounted on supporting brackets 100 and 101 projecting at opposed sides of the base frame, and a third 40 screw jack 99 is mounted on a projecting bracket 103 at the rear of the base frame. Each of said screw jacks consists of an upright screw 105 threaded through its respective supporting bracket and having a horizontally disposed base plate 45 or shoe 106 swiveled at its bottom end, as shown in Figures 5 or 6. Fixed to the upper end of each screw is a suitable head 107, having a plurality of sockets 108 about its periphery for insertion of a turning tool, and also having a recess 109 in its upper surface, adapted to receive the lower pointed end of a mine jack 110. Said mine jack may be of the usual telescopic form 50 including a hand adjusting ring 111. A jack of this kind is detachably mounted between the mine roof and the head 107 of each screw jack, as indicated in Figure 2. With this arrangement, the screw jacks 97, 98 or 99 can be rotated for 55 tilting the machine base plate relative to the floor while they are anchored in place by the mine jacks 110. Said screw jacks can also be employed for tilting the machine when the mine jacks are not in use.

The advantages of the mining machine above 60 described will now be understood as follows: The skid mounting affords a machine of low height so that the machine can be used under lower roof conditions than is possible with track mounted cutting machines. The machine can be moved in any direction along the mine floor so as to be placed at the most advantageous positions relative to the working face. Under most conditions the machine is designed to cut by swinging the turntable while the base frame is anchored in place, but under some conditions the machine can be maneuvered for cutting by means of the cables,

in a manner similar to room and pillar or long-wall mining machines. In either case, however, the screw jacks 97, 98 and 99 can be used to tilt the machine, whenever necessary, for guiding the cutter bar at a desired angle relative to the working face.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a mining machine, a base frame including a skid adapted for slidable supporting engagement with the mine floor, a turntable mounted on said base frame to swing on a vertical axis, cutting mechanism including a chain carrying cutter bar mounted on said turntable, flexible draft means on said base frame for moving the latter along the mine floor, and a plurality of horizontally spaced supporting brackets rigid with said base frame, each having an upright screw member threaded therein and each of said screw members having a shoe at its lower end adapted for slidable supporting engagement

with the ground, and each of said screw members also having a mine jack detachably and rotatably engageable with the upper end thereof for anchoring said shoe relative to the ground, so as to provide tilting adjustment of said base frame and turntable as a whole relative to the mine floor, either while the machine is being moved along the mine floor or is anchored relative thereto.

10 2. In a mining machine, a base frame including a skid in slidable supporting engagement with the mine floor, a turntable mounted at the front of said base frame to swing on a vertical axis, cutting mechanism including a chain carrying cutter bar and a motor for driving the cutter chain mounted on said turntable, flexible draft means for moving said base frame along the mine floor including winding means, a shaft operatively connected with said winding means, a motor on said base frame, gearing connecting said last-named motor with said shaft for driving the latter at variable speeds and in opposite directions, a flexible drive member extending forwardly about said turntable, and means selectively connecting said drive member with said shaft, whereby said turntable may be rotated in either direction at variable speeds.

THOMAS E. PRAY.
